UNITED STATES PATENT OFFICE

1,923,831

SOUND REPRODUCING DEVICE

James G. Juhasz, Chicago, Ill.

Application May 27, 1931. Serial No. 540,445

1 Claim. (Cl. 179—115.5)

This invention relates to sound reproducing devices, and is particularly adapted to be embodied in loudspeakers, and the like, for public addresses and radio receivers.

the magnet member 12 and to standards 27 which support the electro-magnet.

5 One form of the invention is embodied in a loud-speaker which comprises an electro-magnet having a central pole and a pair of opposed outer poles, the construction being such that two relatively narrow arcuate magnetic gaps are provided. A cup-shaped member formed of magnetic material has a cylindrical portion which projects into the magnetic gaps and is mounted in such manner that it may reciprocate along its longitudinal axis. A conical diaphragm has its 10 smaller end secured to the cup-shaped member, and it is provided with a flange at its base, which flange is secured in an annular frame-work.

The operation of the improved sound reproducer is substantially as follows: In accordance with common practice, the winding 16 is connected to a source of direct current so that the electro-magnet is energized. This causes the cup-shaped member 19 to be displaced toward the central pole-piece 11 against the action of the sheet 21. The voice coil or winding 18 is connected to a source of audio frequencies, such as the output circuit of a radio receiver. The varying current in the winding 18 will increase and decrease the strength of the magnetic fields as the current in the voice coil increases or decreases. If it is assumed that the voice coil is mounted in such manner that when the current flowing through it increases, the magnetic fields will be strengthened. It will be readily understood that when the current decreases the magnetic fields will be weakened. Such variance in the flux density in the fields will cause the cup-shaped member 19 to vibrate and it, in turn, will vibrate the diaphragm 22 and reproduce the sounds which produce the signals received by 80

20 Mounted upon the central pole piece is a voice coil which may be operatively connected to the output circuit of a radio receiver, or the like.

In the drawing: Figure 1 is a central longitudinal section taken through a loudspeaker which embodies the invention, and Fig. 2 is a section taken on line 2--2 of Fig. 1. In the drawing: Figure 1 is a central longitudinal section taken through a loudspeaker which embodies the invention, and Fig. 2 is a section taken on line 2--2 of Fig. 1. The magnetic fields will be weakened. Such variance in the flux density in the fields will cause the cup-shaped member 19 to vibrate and it, in turn, will vibrate the diaphragm 22 and reproduce the sounds which produce the signals received by 80

25 Fig. 2 is a section taken on line 2--2 of Fig. 1.
Referring to the drawing wherein a preferred
embodiment of the invention is illustrated, the
reference character 10 designates generally an
electromagnet which comprises a central pole
30 piece 11 and a U-shaped pole piece 12 provided
with inwardly turned ends 13. The central pole
piece 11 projects into the space between the ends
13 in such manner that two arcuate magnetic
gaps 15 are formed. The winding for the elec-
35 tro-magnet is shown at 16, the winding 16 being
carried by the central pole piece 11. Also mounted
upon the central pole piece 11 is a voice coil 18
which may be connected to the output circuit, on
a radio receiver, or the equivalent.

While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention as broadly as possible, in view of the prior art. 85 90

What I claim as new, and desire to secure by Letters Patent, is:

40 A cup-shaped member 19 formed of magnetic material is provided with a cylindrical flange 20 which projects into the arcuate gaps 15. The sheet 21 may be made of impregnated fabric or sheet metal. The construction is well known in
45 the art and it is readily understood that the sheet 21 is adapted to restore the cup-shaped member 19 to its neutral or unbiased position after it has been displaced as hereinafter explained.

A sound reproducing device comprising an electro-magnet having a central pole-piece and an outer pole-piece, said pole-pieces co-operating to form an annular magnetic field, a winding on said central pole-piece adapted to be connected to a source of direct current to energize the electro-magnet, a second winding on said central pole-piece adapted to be connected to a source of current modulated by audio-frequencies, a cup-shaped member formed from magnetic material and provided with a cylindrical wall disposed in said magnetic field, a flexible member supporting said cup-shaped member for movement in said field, and a conical diaphragm having its smaller end fixed with respect to said cup-shaped member. 95 100 105
